SHAVING IMPLEMENT

John A. Hanley, Noroton, Conn., assignor to Gillette Safety Razor Company, Boston, Mass., a corporation of Delaware

Application May 8, 1941, Serial No. 392,438

10 Claims. (Cl. 30—43)

The present invention comprises a novel shaving implement which, if desired, may be carried in the pocket of the user and used for shaving without lather or other preparation, or for cleaning up the face during the day as a supplement to a more extended shaving operation. The invention is herein shown as embodied in an implement having a sharp stationary blade or blades and a co-operating roller movable by frictional engagement with the face and provided with hair-receiving openings arranged to pick-up and support the individual hairs as they are presented to the sharp edged blade. Dry shaving with a sharp edged blade is almost unbearable for most users on account of the pulling action of the blade in severing an un-supported hair. In accordance with the present invention, however, each hair to be severed is entered in an aperture of the roller and the implement as a whole is moved to bring the hair into cutting relation with the blade while the outer portion thereof is supported by extending into one of the roller openings. In this way pulling is avoided and a comfortable shaving operation insured.

With these ends in view, important features of my invention consist in means for securely and accurately supporting one or more blades with their sharp edges resting upon the outer surface of an apertured roller at an angle to the plane of tangency; in providing spring-operating clamps for removably holding the blades in position; in providing means for preventing accidental releasing of the blade clamps, and in providing a novel form of ring bearing for the roller which simplifies the construction of the implement and reduces friction therein.

An important feature of the invention consists in a curved cutter plate, in this case taking the form of a roller, which directly engages the face of the user and then passes downwardly or inwardly beneath an external cutting blade which is also engaged by the face. This novel combination of cutting elements results in very close shaving action—much closer than in those implements where the cutting action takes place at the inner face of a cutter plate through which the hairs must project to reach the shearing plane.

These and other features of the invention will be best understood and appreciated from the following description of a preferred embodiment thereof, selected for purposes of illustration and shown in the accompanying drawing, in which:

Fig. 1 is a view of the implement as seen from above and on an enlarged scale;

Fig. 2 is a view in elevation of one form of roller;

Fig. 3 is a view of the implement as seen from one end, a portion of the frame being broken away;

Fig. 4 is a corresponding view in elevation;
Fig. 5 is a sectional view of a roller and a mounting of an alternative form;
Fig. 6 is a central sectional view corresponding to Fig. 5.

5 The implement in the form herein illustrated comprises a one-piece frame 10, rectangular in outline and having a deep central longitudinal recess forming spaced blade-supporting walls at either side. The frame 10 may be formed of wood or moulded from suitable plastic material. The blade-supporting walls which extend along both sides of the frame are shaped at their upper edges to provide inwardly and upwardly inclined 10 blade seats. As shown in Figs. 1, 3 and 4 an elongated hollow roller 12 is journaled to rotate freely upon or with a shaft 23 in the recess of the frame between these blade seats. At both ends the roller is provided with circular apertured beads through which project the shaft 23. 15 The roller 12 may be constructed of thin sheet steel and is provided with a multiplicity of small openings or apertures 12 in its cylindrical surface. These apertures are designed to receive the individual hairs or stubble on the face of the user as the implement is moved and the roller rotated by frictional engagement with the surface being shaved.

20 The implement is provided with a handle 14 which as herein shown may be formed from sheet steel and comprises two downwardly extending branches bent from opposite sides of a base plate 15 secured by screws or otherwise to the bottom of the frame 10. The base plate is bent upwardly at both ends and shaped to provide tapering end plates 16 serving to hold the roller 12 in place against endwise movement. As herein shown the blade seats present the blades to the roller at an angle of about 22° 25 to a tangent plane at the line of blade contact, or at an angle greater than 90° to a radius to the line of contact. As shown in Fig. 3 the ends of the roller are perforated to permit the escape of shaving debris and these end perforations are arranged so as partially to clear the stationary end plates 16 which supply bearing for the shaft 23.

30 A pair of straight narrow blades 17 are retained upon the blade seats by clamps 18. These clamps are formed of sheet metal and each includes an upper portion which overlies the blade, a pair of ears 18 by which the clamp as a whole is pivoted to the frame and downturned lugs or ears 20 which embrace ends of the blade 17 and prevent endwise movement thereof. The clamps 18 are reduced in width at their lower edge and bent outwardly to provide finger pieces and against which spiral compression springs 21 are arranged to act, tending always to close the clamps. The bodies of the springs 21 are

received within sockets provided for that purpose in the frame 10 as shown in Fig. 3.

The clamps 18 may be retracted by inward pressure on the finger pieces at their lower edges to release the blade 17 for replacement or cleaning and, to insure that such releasing movement should not accidentally occur with risk to the user, each clamp is provided with a check screw 22 which passes through a hole in the clamp and is threaded into the frame 10. The head of the screw engages the outer face of the clamp and prevents releasing movement of the clamp unless the screw is first loosened.

The shape of the openings in the roller is of secondary importance so long as they are effective to receive the hairs projecting from the face of the user and to move with the hairs up to the edge of the blade and so support them during the cutting operation. The roller 12 is shown as provided with a multiplicity of small openings arranged in parallel rows and this represents one satisfactory construction. A modified roller 25 is shown in Fig. 2 wherein the openings take the form of undulating slits 26. Numerous other forms of hair-receiving openings may be employed within the scope of the invention.

In operation the implement is passed over the face of the user with a firm pressure upon the exposed cylindrical surface of the roller 12 in which sufficient traction is developed to cause turning of the roller without slipping. The hairs engaged by the openings in the roller are thus brought to the edge of one blade or the other according to the direction of movement of the implement and are supported during the severing operation so that a smooth shave without pulling is effected. The implement as already intimated may be carried by the user and employed in spare minutes to clean up the face and improve the appearance.

The roller shown in Figs. 3 and 4 has a perforated head in each end carrying or turning upon the transverse shaft 23. The roller 12 in Figs. 5 and 6, on the other hand, is shown as 45 fully open at both ends and has no internal shaft. By this alternative construction the escape of shaving debris from the implement is expedited. The open-end roller is rotatably and externally supported by semi-circular ribs 11 provided by countersinking the central zone of the frame 10 and thus forming spaced bearings at each end of the roller. The illustrated implements are shown as having blades on both sides of the roller 12 and, while this arrangement is desirable in that it permits shaving while the implement is moved in both directions on the face, it would be within the scope of the invention to employ a single blade only.

It will be observed that the blade clamps 18 are independently operated, each by its own spring, and therefore the pressure of the blade edges against the roller is independently determined and limited. The location and spring pressure of the blades are effective to hold the roller 12 in place upon its open ring bearings 11 when this construction is employed. In both constructions the springs 24 are effective to hold the blades firmly though yieldingly in contact with the surface of the roller and the angular shape of the clamps is such that the blades are prevented from retracting movement. The blade angle may be varied by varying the width of the blade or the angle of the blade seat.

Having thus disclosed my invention and de- 75

scribed in detail the best embodiment thereof now known to me, I claim as new and desire to secure by Letters Patent:

5 1. A shaving implement comprising a frame, a roller mounted therein for rolling engagement with the face of the user and having hair-receiving openings in its surface, and a blade bearing longitudinally at its edge upon the outer surface of the roller.

15 2. A shaving implement comprising a frame, a roller journalled in the frame and having hair-receiving openings in its surface, and a straight-edged blade maintained in yielding engagement with the surface of the roller, whereby hairs entering the openings of the roller are supported while severed by the blade as the roller travels over the face of the user.

20 3. A shaving implement comprising a frame, an apertured roller journalled therein, and a sharp edged blade maintained with its edge against the surface of the roller at an angle to the tangent plane at the line of blade contact.

25 4. A shaving implement comprising a frame, an apertured roller journalled therein for rotary movement in either direction in traction on the face of the user, and sharp edged blades disposed at opposite sides of the roller with their edges contacting with the roller with an unobstructed area of the roller exposed between them.

30 5. A shaving implement comprising a frame having a recess, an apertured roller journalled in the frame to rotate in said recess, a pair of straight edged blades arranged to engage the roller with a space between their lines of contact, and separate means for pressing the respective blades upon the roller.

35 6. A shaving implement comprising a frame having a recess therein shaped to present spaced ribs forming semi-circular bearings, an apertured roller journalled in said bearings, blades co-operating with said roller, and spring pressed members acting through the blades to hold the roller in place in said bearings.

40 7. A shaving implement comprising a frame having a recess therein shaped to present open bearings, an apertured roller journalled in said bearings, blades co-operating with said roller and acting also to hold it in place in said bearings, and means for preventing longitudinal movement of said roller.

45 8. A shearing implement comprising a frame having a recess for a rotary apertured roller, blades engaging the roller in spaced relation to each other, spring clamps mounted in corresponding positions on either side of the frame whereby they may be operated simultaneously to release the blades, and positive means for preventing the accidental release of the clamps.

50 9. A shaving implement comprising a frame having an apertured roller mounted therein for tractive rotation on the face of the user, a flat blade arranged to bear with its edge in fairly rigid engagement upon said roller, and a clamping device shaped to prevent the blade from backing away from the roller.

55 10. A dry shaving implement comprising a head having a stationary sharp-edged blade disposed in position to be engaged at its edge upon the face of the user, and a thin, perforated, cylindrical segment of sheet steel movable in a circular path toward and beneath the edge of said stationary blade and located also to make direct engagement with the face of the user.

JOHN A. HANLEY.
